UNITED STATES PATENT OFFICE

ANTHONY DI LUCCI, OF CHICAGO, ILLINOIS, ASSIGNOR TO APPLIED RESEARCH, INC.,
OF CHICAGO, ILLINOIS, A CORPORATION OF ILLINOIS

DESIGN FOR A LAMP

Application filed July 29, 1929. Serial No. 32,241. Term of patent 14 years.

To all whom it may concern:

Be it known that I, ANTHONY Di LUCCI, a citizen of Uruguay, residing at Chicago, in the county of Cook and State of Illinois, have invented a new, original, and ornamental Design for Lamps, of which the following is a specification, reference being had to the accompanying drawing, forming a part hereof.

Fig. 1 is a front elevational view of a lamp showing my new design.

Fig. 2 is a side elevational view of the lamp shown in Fig. 1.

Fig. 3 is a plan view of the lamp hood forming a part of the design shown in Figs. 1 and 2.

I claim:

The ornamental design for a lamp, substantially as shown.

ANTHONY DI LUCCI.
